UNITED STATES PATENT OFFICE

145,274

DESIGN FOR A LAMP SHADE WITH LUMINOUS FIGURES

James Ross, Hubbard Woods, Ill.

Application January 11, 1945, Serial No. 117,378

Term of patent 3½ years

(Cl. D48—16)

To all whom it may concern:

Be it known that I, James Ross, a citizen of the United States, residing at Hubbard Woods, in the county of Cook and State of Illinois, have invented a new, original, and ornamental Design for a Lamp Shade with Luminous Figures, of which the following is a specification, reference being had to the accompanying drawing, forming a part thereof.

Figure I shows an elevational view of the lamp shade with luminous figures embodying my design.

Fig. II is a fragmentary section taken on line 2—2 of Figure I.

The lamp shade is circular in horizontal section throughout its height, and the side not shown is a substantial duplicate of that illustrated in Fig. I.

I claim:

The ornamental design for a lamp shade with luminous figures, substantially as shown and described.

JAMES ROSS.
